UNITED STATES PATENT OFFICE.

CONRAD WERRA, OF WAUKESHA, WISCONSIN.

RADIATOR.

Application filed April 25, 1925. Serial No. 25,816.

This invention relates to improvements in radiators, more particularly adapted for internal combustion engine use.

Automobile engine radiators as now ordinarily made, have a surrounding casing formed of a number of parts connected together and surrounding the radiating portion which is of the tubular or honeycomb type.

These constructions form many joints which are comparatively frail and are easily damaged and leak, and when damaged they cannot be easily repaired.

It is one of the objects of the present invention to overcome the before mentioned objectionable features and provide a radiator casing formed of a one-piece casting into which tubular radiator members extend.

A further object of the invention is to provide a radiator in which the radiating units may be easily repaired or replaced in the event of injury.

A further object of the invention is to provide a radiator having means for preventing dust or other foreign substances from lodging in the radiating units.

A further object of the invention is to provide a radiator which is of simple construction, is strong, durable and efficient, and is well adapted for the purpose described.

With the above and other objects in view, the invention consists of the improved radiator and its parts and combinations as set forth in the claims, and all equivalents thereof.

In the accompanying drawing in which the same reference characters indicate the same parts in all of the views:

Fig. 1 is a front view of the improved radiator, parts broken away to show interior construction;

Fig. 2 is an edge view thereof with parts broken away to show interior construction;

Fig. 3 is a vertical sectional detail view taken on a larger scale through one of the radiator tubes and connected parts.

Fig. 4 is a vertical sectional detail view taken on line 4—4 of Fig. 3;

Fig. 5 is a transverse sectional detail view of a modified form of radiating unit; and

Fig. 6 is a vertical sectional detail view of another modified form of radiating unit.

Referring to the drawing, the numeral 8 indicates a rectangular casing consisting of a front wall 9, a rear wall 10, and top, bot-

tom and opposite side edge walls, 11, 12 and 13, respectively. The front and rear walls are spaced from each other by the top, bottom and side walls and also by cross brace pins 14, and the opposite side edge portions of the casing are formed with projecting lugs 15 for attaching the casing to the frame of an automobile. The parts thus far described are preferably, but not necessarily, formed of aluminum, and in a single or integral casting, as shown. The casing is also formed with an upper inlet opening 16, lower discharge openings 17 and 17' and an upper filling opening 18 closed by a cap 19.

The front and rear walls 9 and 10 of the casing are formed with registering inwardly extending annular bosses 20 forming shouldered flue openings 21 staggered with relation to each other, for receiving horizontal air flue tubes 22. Said tubes have their opposite end edges flanged over the shoulders of the openings, as indicated by the numeral 23, to form a water tight connection therebetween. Concavo-convex screen caps 24 are tightly fit into the ends of the flue openings 21 to prevent the entrance of dust or other foreign matter into said flues.

Each flue tube is provided or formed with inner radiating flanges or fins 25 which may be of various forms as desired. In the form shown in Figs. 1 to 4 inclusive, a flat strip of metal is twisted a one quarter turn before being welded, soldered or otherwise fastened within the tube to impart a circular movement to the air and cause it to frictionally engage the strip and the inner side surface of the tube and absorb the heat therefrom. The tubes and fins are preferably formed of copper, but other metals may be used. The rear wall of the casing is formed with a flange 26 for engagement with the hood of the automobile and also to reinforce the casing.

In the form shown in Fig. 5, the tube 22' is crimped or corrugated inwardly intermediate its ends to form increased radiating surfaces 28, and in the form shown in Fig. 6, a number of inwardly extending flanges or fins 27 are secured to the inner surface of the tube to provide increased radiation.

From the foregoing description it will be seen that the radiator is of very simple and rigid construction and that if any of the flue tubes should leak or become damaged, they can be easily removed and others substituted therefor and secured in position.

What I claim as my invention is:

1. A radiator, comprising a casing having spaced front and rear walls provided with annular recesses forming shouldered openings, and air flue tubes extending through the openings of each wall and having their opposite ends flanged and the flanged portions extending into the recesses to form a tight joint with the shouldered portions of the openings, said tubes having inner radiating fins.
2. A radiator, comprising a one piece casing having opposite walls provided with registering annular recesses forming shouldered openings, horizontal flue tubes extending into the openings and having flanged end portions which enter the annular recesses and engage the shoulders to form a tight connection therewith, and means within the tubes for causing air to travel in circuitous paths through the tubes.
3. A radiator, comprising a one piece casing having opposite walls provided with registering annular recesses forming shouldered openings, horizontal flue tubes extending into the openings and having flanged end portions which enter the annular recesses and engage the shoulders to form a tight connection therewith, and spirally twisted fins positioned within the flue tubes.
4. A radiator, comprising a one piece casing having opposite walls provided with registering annular recesses forming shouldered openings, horizontal flue tubes extending into the openings and having flanged end portions which enter the annular recesses and engage the shoulders to form a tight connection therewith, screen means at the ends of the tubes for preventing the entrance of foreign matter into the tubes, and spirally twisted fins positioned within the flue tubes.
5. A radiator, comprising a one piece cast casing having front and rear walls provided with registering annular recesses forming shouldered openings, said openings formed with annular shoulders, the front and rear walls being spaced from each other and connected together by a plurality of brace pins cast integral with the walls, flue tubes extending into the openings and having flanged end portions which enter the openings and engage the annular shoulders to form tight connections therewith, and means for causing air to travel in circuitous paths through the tubes.

In testimony whereof, I affix my signature.

CONRAD WERRA.
